UNITED STATES PATENT OFFICE.

FREDERICK WILLIAM SCHROEDER, OF LONDON, ENGLAND.

LOCK.

1,357,122.

Specification of Letters Patent. Patented Oct. 26, 1920.

Application filed April 19, 1920. Serial No. 375,107.

To all whom it may concern:

Be it known that I, FREDERICK WILLIAM SCHROEDER, a subject of the King of Great Britain, residing in London, England, have 5 invented certain new and useful Improvements in Locks, of which the following is a specification.

This invention relates to locks of the latch type such as are used in connection with pin 10 tumbler locks, and are provided with means controlled by the movements of the lock handle and adapted to hold the bolt of the latch lock fast in either its forward or protruding position or in the backward or 15 withdrawn position, the holding or locking of the bolt in its backward or forward position being effected by a further movement of the handle of the lock beyond that necessary for shooting the bolt back or forward, such further movement being effected 20 in opposition to spring resistance, so that it is rendered difficult of accomplishment by a child.

The invention consists in an improved 25 construction of the mechanism whereby the bolt of a latch lock of the above kind is operated and locked in the forward and backward position.

According to the invention the bolt is 30 connected with a bent plate slidably mounted in the lock casing and adapted to be actuated or moved to and fro by an arm on the spindle of the lock handle, the plate being provided with integrally formed 35 spring portions that are described below and tend to check the movements of the handle and the actuating arm thereon.

The improved lock may be provided with known means, as hereinafter described, for 40 preventing the lock bolt being operated or forced into its back or inoperative position by an unauthorized or other person from outside the door by means of a suitable instrument or appliance inserted or pushed 45 into the crevice between the front end face of the lock and the usual striking or catch plate casing carried either by the door frame or jamb lining, or in the case of folding doors by the fellow or companion door, 50 the appliance being inserted so that its forward end bears against the customary beveled end of the bolt thereby and thus pushes it toward its back position.

The invention will be described with 55 reference to the accompanying drawings, which show a latch lock and parts for

operating its bolt. In the drawings Figure 1 is an elevation of the inner side face or that face of the latch lock casing which, when the lock is fixed to a door, will be in 60 contact with the inside face of the door; Fig. 2 is a sectional plan on the line II—II in Fig. 1, the bolt catch or striking plate casing fixed to the door frame or companion folding door being also included; Fig. 65 3 is an elevation of the lock casing in Fig. 1 with the inner side face plate removed to show the bolt operating and locking means; Figs. 4 and 5 are elevations of a spring member and rocking arm adapted to co- 70 operate therewith, which constitute parts of the operating and locking means shown in Fig. 3, the arm being shown in different positions in the respective figures; and Fig. 75 6 is a perspective view of the above-mentioned spring member.

In the drawings *a* denotes a spindle or barrel which is rotatably mounted in the lock casing and adapted to be turned by a person from the inner side of the door *b* 80 by means of the knob or handle *c* which is in one with or fixed to the spindle. The lock casing may be formed in any suitable manner but is here shown to consist of a part *d* constituting the main portion of the case 85 and a removable part *d'* constituting the side face that is adjacent to the inner face of the door when the lock is mounted on the latter. The part *d'* can be engaged with or secured to the part *d* in any suitable manner, as for instance by means of the interengaging lugs *d*², *d*³ on the respective parts and by screws *e* that screw into lugs *d*⁴ on *d'*.

The bolt *f* having the usual beveled front 95 end face *f'* is attached in a customary manner to a pair of backwardly extending pins *i* which pass through a yoke plate *g*, coil springs *h* encircling the pins *i* being interposed between the back end face *f*² of the 100 bolt and the plate *g*. The springs *h* tend to press the plate *g*, against the lugs *d*⁵ on the part *d*.

The spindle *a* has fixed on it inside the interior of the lock case a disk *j* having a 105 single extending arm *j'* thereon, the outer end *j*² of which may be bent inward or at an angle to the arm face, and be provided at the center of the said bent portion with a small indentation. This arm is arranged 110 to co-operate with a slidably mounted spring plate which is of peculiar bent construction.

and attached to the rear ends of the pins *i* as best seen in Fig. 6. The said spring plate has a front part comprising a forwardly projecting portion *k* (Fig. 3), two substantially vertical or straight parts *k'*, *k*² to which the pins *i* are connected, an upper or longitudinal part *k*³ and a rear part *k*⁴. The plate is so stamped as to have three spring portions *k*⁵, *k*⁶, *k*⁷ formed thereon and in a manner to yield or spring when engaged by the end *j*² of the arm *j*' when the lock handle *c* is operated either to move the bolt backward or forward, or to hold the bolt backward in a locked position, or 15 to hold it forward in a locked position. The spring portion *k*⁵ is provided with a projection *k*⁸ for a purpose mentioned below.

In order to carry out the first operation, 20 the handle *c* and spindle *a* are moved around in a direction to cause the internal arm *j*' to move away from the normal position indicated in Fig. 3, and to travel over the spring *k*⁵ carried by the back portion *k*⁴; 25 the continued movement of the arm forces the plate backward against the pressure exerted by the springs *h*, thus withdrawing the pins *i* and the bolt *f* from its forward or locking position, Figs. 1, 2 and 3, to 30 the back or open position. Further continued movement of the handle is checked by coming in contact with projection *k*⁸ referred to above. Should the handle be released the bolt is returned to its normal 35 position by the reaction of the springs *h*. In order to hold the bolt locked in the said backward position the handle is turned around still farther in the above mentioned direction, forcing the bent up end of arm 40 *j*' over the projection *k*⁸ so that the notch in the end *j*² snaps on to the projection as shown in Fig. 4. The end of the back portion *k*⁴ may be bent in such a manner that it will project into the path of the arm to 45 prevent further turning of the arm in that direction, should the latter be turned so far. Such a bent part or strip is shown at *k*⁹, Fig. 4.

In order to fasten the bolt in its forward position the handle is turned in the reverse direction until it comes in contact with spring portion *k*⁶ over which it can be forced and thus enable the end of arm *j*' to slide over the spring portion *k*⁷ and 55 into engagement with the projecting part *k* of the plate, as indicated in Fig. 5, which thus prevents the movement of the bolt backward. In like manner the handle can be turned backward and forced over the 60 spring portions *k*⁷ and *k*⁶ into the normal position, Fig. 3, in order to unlock the bolt.

The bolt *f* may in known manner be drawn backward against the action of the springs *h* and independently of the handle 65 *c*, by a person on the outer face of the door,

so as to open the door by means of any suitable key-actuated device associated with the parts shown in the drawings. Such a device comprises a barrel piece *l* (Fig. 1), rotatably mounted on the inner face plate 70 *d'* and provided with a longitudinally extending slot *l*'. To the barrel is fixed a disk *m* having two arms *m'*, *m*² that are shaped and arranged respectively to engage operatively with the front face of the parts *k'* 75 or *k*² of the above mentioned spring plate when the barrel *l* is turned in one direction or the other.

For turning the barrel *l* a removable key, which is not illustrated, but may be of any 80 suitable known form, would be employed; such key having a part so shaped and arranged that when the key is inserted in slot *l*' it engages or bears against the sides thereof so that upon the key being turned 85 the barrel will be likewise turned.

The parts *m'*, *m*² engaging the front face of the spring plate to which the pins *i* are rigidly attached, limit the extent of the forward movement of the bolt and associated parts. 90

Any suitable known means may be provided to prevent the bolt, when in its front or locking position and in engagement with the striking plate or catch casing *n* fixed to the door frame or a companion door *o*, from being pushed toward its back or open position by a person outside the door by means of a suitable instrument pushed from outside through a hole bored or cut for the purpose, through the door frame *o*, into the crevice between the front end face *d*⁵ of the casing and the adjacent end of the casing *n*, and against the beveled front face *f*' of the bolt. The means shown consist of an 100 outwardly extending lip or flange piece *n*' integral with or attached to the casing *n*, which piece may be suitably secured to the side face of the rabbet *o*' of the door frame, as for instance by means of screws *p*. The 105 flange piece *n*' is preferably provided with a chamfered face *n*² so that it presents a surface difficult to bore out. It will be seen from Fig. 2 that this piece *n*' effectually masks the joint or opening between the 110 door lock and its catch, and prevents the insertion of any instrument therethrough to move the bolt back.

Having thus described the nature of the said invention and the best means I know 115 of carrying the same into practical effect, I claim:—

1. In a latch lock of the kind referred to, the combination of an inclosing case, a latch bolt arranged therein and to slide forwardly 120 into a locking position and backwardly into an unlocking position, a spindle rotatably mounted in the casing, an operating handle carried by the spindle, an arm fixed at one end to the spindle, and means actuated by 125

the turning movements of the arm for operating the bolt and locking it both in its locking and unlocking positions, said means comprising a bent plate, having a front part, 5 a back part, and a part connecting the said front and back parts, the front and back parts each comprising a projecting portion and an integrally formed spring portion yieldable when engaged by the free end of 10 the arm, said arm adapted, when the handle and spindle are turned a predetermined amount in one direction, to engage with the spring portion on the said front part, thereby by moving the plate and bolt forwardly into 15 a locking position, and on further movement of the handle and spindle in the said direction to engage in the projection on the front part, thereby locking the bolt in the locking position, said arm being also adapted, when 20 the handle and spindle are turned in the opposite direction, to engage with the spring portions on the said back part, thereby retracting the plate and bolt into an unlocking position and on further movement of handle 25 and spindle in said opposite direction to engage with the projection on the said back part, thereby locking the bolt in the unlocking position.

2. In a latch lock of the kind referred to, 30 the combination of an inclosing case, a latch bolt mounted therein to slide forwardly into a locking position and backwardly into an unlocking position, a spindle rotatably mounted in the casing, an operating handle 35 carried by the spindle, an arm fixed to the spindle adjacent one end, means actuated by the turning movements of the arm for

operating the bolt and locking it both in its locking and unlocking positions, said means comprising a bent plate having a front part, 40 a back part and a part connecting the said front and back parts, the front and back parts each comprising a projecting portion and an integrally formed spring portion, said arm adapted when the handle and spindle are turned a predetermined amount in 45 one direction to engage with the spring portion on the said front part, thereby moving the plate and bolt forwardly into a locking position, and on further movement of the handle and spindle in the said direction to engage with the projection on the front part, thereby locking the bolt in the locking position, said arm being also adapted, when the handle and spindle are turned in the opposite 50 direction, to engage with the spring portion on the said back part, thereby retracting the plate and bolt into an unlocking position, and on further movement of handle and spindle in said opposite direction to 55 engage with the projection on the said back part, thereby locking the bolt in the unlocking position, and a key actuated device for moving said bent plate and latch bolt backwardly from the locking position independently of the handle and spindle, said device comprising a barrel piece rotatably mounted in the said case, and a disk fixed to said barrel piece and having a pair of oppositely directed arms adapted to engage with the 60 front part of the bent plate.

In testimony whereof I have signed my name to this specification.

F. W. SCHROEDER.
